UNITED STATES PATENT OFFICE.

LEWIS MOORE AND CLAUDE M. DIBBLE, OF JOLIET, ILLINOIS, ASSIGNEES TO MOORE BROTHERS COMPANY, OF JOLIET, ILLINOIS, A CORPORATION OF ILLINOIS.

REVERSIBLE STOVE.

Application filed November 2, 1925. Serial No. 66,243.

This invention relates in general to reversible stoves and while the invention is hereinafter more fully explained in connection with an electric stove, it will be manifest 5 that other heating mediums may readily be employed, as, for example, gas or oil.

A principal object of the present invention is the provision of a stove having the usual burner box for open cooking and having also 10 oven and broiler parts which may be installed at will as a right or left hand stove, or may have its parts separated and located in different parts of the same kitchen, all as particular conditions and space arrangement render desirable.

Another important object of the invention is the provision of a stove constructed of two 20 divisible units as the burner box, as one unit, and the oven and broiler, as a second, which may be erected in desired right or left hand stove assembly without need of providing a fixed frame for the purpose and which on the other hand will merely require that the two parts be connected together in simple fashion 25 and the whole supported upon legs attached directly to the exposed corners or ends of the assembly.

Another important object of the invention is the provision of means for providing heating 30 medium, which will be easily adapted to all of the arrangements of which the construction is capable.

Numerous other objects and advantages of the invention will be apparent as it is better 35 understood from the following description, which, taken in connection with the accompanying drawings, discloses a preferred embodiment thereof.

Referring to the drawings, 40 Figure 1 is a perspective view taken from the rear of an electric stove in which our invention is embodied;

Fig. 2 is a similar view taken from the front and with the parts as yet unconnected; 45 and

Fig. 3 is a detail section showing the connection between the lower portions of the adjacent faces of the arranged parts.

For the purpose of illustrating our invention, we have shown on the drawing two separate stove parts indicated by reference characters 11 and 12. The part 11 is a combined oven and broiler part, which may have any usual or preferred construction, and the part 55 12 similarly is a burner box part having the

usual open burners 13 and warming shelf 14. Each of these parts is complete in itself and is provided at its bottom with a relatively heavy band or reinforcing member 15. Each said part is constructed for attachment 60 to a similar portion of the band of the companion part at each corner and to suitable stove legs or to suitable stove legs only.

This provision for the joining of the stove parts to each other or to the legs consists in 65 two apertures 16 arranged on each face adjacent the corner. Stove legs are indicated at 17 of any usual or preferred construction, adapted, however, for engagement with four openings 16 at a corner, two of such openings 70 as has been mentioned being located at the meeting faces of the stove. Bolts 18, as indicated in Fig. 3, are provided to hold either the stove legs or the stove parts together when arranged through registered openings 16. 75

The parts are arranged in Fig. 2 to be assembled into a right hand oven stove. This is accomplished by bringing the two parts so that the exposed side faces of the part 11 is in contact with the hidden side face of the part 12. The bolts 18 are then arranged through the openings 16 which are then brought into alignment and thus screwed 80 home. The legs are attached in the usual manner, the bolts extending through the opening 16 at the four corners of the resulting assemblage. 85

The stove may be reversed so that the burner box is to the right of the oven part by removing all the bolts mentioned and bringing 90 the exposed side face of the burner box up against the hidden side face of the oven part; bolts threaded through the aligned openings, then will permit of the tight assemblage of the unit in the opposite or reversed relation 95 of its parts. Similarly then the legs may be positioned upon the exposed corners of the resulting assembly to support the stove in service.

It is thought unnecessary to fasten the adjacent stove sides to each other except at the bottom because the arrangement of the legs on the two parts at their outer sides tends to bring the tops of the parts into tight engagement by gravity and the tension upon the bolts extending through the openings 16 is all that is needed to rigidly assemble the construction. Of course, other and additional fastening means may be employed if desired. 100 105

Each one of these stove parts is so con- 110

structed therefore as to permit of the arrangement of four legs for each part and their separate erection in different parts of the same room or, for that matter, in different localities entirely, merely by attaching four supports to the corner of the particular stove part in the manner already described for attaching them at two corners.

The stove shown on the drawings of this application employs electricity as a heating medium and we have shown upon the back of each stove part a connection box 21 having openings 22 at each side or end thereof. A connector conduit 23 may extend between these connection boxes when the stove is erected and carry the wires 24 supplying electricity from the one part to the other. When the stove is reversed, the conduit 23 may extend out from the lefthand opening 22 of the present lefthand connection box into the righthand opening 22 of the righthand connection box, or when the stove parts are used separately separate supply lines can go to the two connection boxes.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being nearly a preferred embodiment thereof.

We claim:

1. A stove, comprising a combined oven section and a burner box section, said sections being formed for reversible adjacent arrangement, and means arranged at the opposite sides of each section for securing adjacent faces of said parts together to combine the sections into a unitary stove construction, said means being also adapted for attaching supporting legs to said sections.

2. A stove, comprising a combined oven part and a burner box part, said parts being adapted for reversible side by side arrangement, and means in each part for securing said parts together, said means also providing for the attachment of supporting legs to said parts.

3. A stove, comprising a combined oven part and a burner box part, said parts being adapted to be reversibly arranged in adjacent relationship and having separate support

bases, means for supporting attaching members to the corners of said bases, said means being arranged in the ends of a said base and providing means for securing adjacent faces of said parts together to provide a rigid unit stove assembly.

4. A stove, comprising a combined oven part, and a burner box part adapted to be reversibly arranged in adjacent relationship, means in both parts for attaching either of said parts upon either side of the companion part, said means being adapted to attach legs at the exposed ends of said parts.

5. A stove, comprising a combined oven part, and a burner box part adapted to be reversibly arranged in adjacent relationship, each said part having a separate supporting base forming a part of the section, each said base having means arranged at the corners of the supporting base for attaching stove legs or for attaching the base to its companion.

6. A stove, comprising a combined oven part and a burner box part adapted to be reversibly arranged in adjacent relationship, means arranged on each said part at the corners thereof providing for the attachment of legs for separately supporting each part, said means providing for securing said parts together when arranged in adjacent relationship, one part being arrangeable on either side of the companion part to provide a unit combination stove having four legs arranged at the exposed corners of the two parts to support the combined stove as a single stove assembly.

7. A stove, comprising a combined oven part and a burner box part adapted to be reversibly arranged in adjacent relationship, means in each part for attaching a said part upon either side of its companion part, each said part being supplied with a heating medium supply circuit including control means, and means adapted for interconnecting said supply circuits for both adjacent arrangements of said parts.

8. A stove, comprising a combined oven part and a burner box part adapted to be reversibly arranged in adjacent relationship, each said part being provided with a heating medium supply means including an inlet and reversible pipe for interconnecting said inlets for both adjacent arrangements of said parts.

LEWIS MOORE.

CLAUDE M. DIBBLE.
